UNITED STATES PATENT OFFICE.

FRANK J. SCHLEICHER, OF ST. LOUIS, MISSOURI.

BOX.

Application filed July 15, 1927. Serial No. 205,909.

This invention relates to a paper or cardboard box formed approximately in the shape of a horse shoe with its curved side wall extending around the curved outer side of the box conforming to the outer side of a horse shoe, and an inwardly curved side wall portion connecting the ends of said first side wall portion.

An object of the invention is to improve the construction of such box by providing a side wall composed of a single piece of material having one edge attached to the top or the bottom of the box and having its ends connected at one of the corners, and improved means for strengthening the connection of the side wall with the top or bottom of the box throughout the length of the side wall.

Another object of the invention is to improve the construction of a "horse shoe shaped" box whereby the manufacture or production of the boxes is facilitated, and the cost of manufacture reduced and a better product obtained.

Other objects will appear from the following description, reference being made to the drawing in which

Fig. 1 is a plan view of my improved box with a part of the outer sheet being broken away to show clearly the construction by which the side walls are attached to the top and bottom of the box, respectively.

Fig. 2 is a sectional view on the line 2—2 of Fig. 1.

Fig. 3 is a perspective view showing one of the inner corners of the box whereby the ends of the side walls are connected.

Fig. 4 is a perspective view showing one of the outer corners of the box.

The top and bottom of my improved box are of duplicate construction, except that the side wall of the top encloses a slightly larger area than the side wall of the bottom, so that, when the top is placed on the bottom, the side wall of the top closely surrounds the side wall of the bottom of the box. Since the top and bottom are of duplicate construction with this exception, a description of one applies also to the other, and like reference numerals are applied to similar parts of the top and bottom of the box.

The top and bottom of the box each comprises an outer section 1 of cardboard or similar material having the greater portion of its edge curving generally to resemble the outer edge of a horse shoe, and having an

inwardly curved portion forming the edge intersecting the outside curved portion and forming therewith sharp corners 2; and an inner section 3 of slightly smaller area than the outer section 1, but of precisely the same shape.

The outer wall of the bottom and the top of the box, respectively, comprises an elongated strip 4 of cardboard or the like of a length slightly greater than the distance around the inner section 3. At a distance from one longitudinal edge of this strip 4 a score line 5 is formed throughout the length of said strip and parallel with its edge. That part of the strip between the score line 5 and the adjacent edge is provided with notches 6 extending to said score line, most of which notches are approximately V-shaped and which are at varying distances apart, as will be understood by reference to Fig. 1. The tongues 7 formed by these notches 6 are bent laterally along the score line 5 at right angles between the inner and outer bottom and top sections 1 and 3, so that the walls 4 bear closely against the edges of the inner top and bottom sections 3. The outer edge 8 of the tongue 7 at the end of the wall 4 is cut on an incline and approximately bisects the angle 2 at the corner of the box. In placing the wall 4 about the inner section 3, the end 9 of the wall 4 on which the tongue 7 is formed, as described, is positioned at one of the corners 2 of the section 3; and said wall 4 is then curved around the outwardly curved edge of the section 3 to the opposite corner 2 of said section where a tongue 10 similar in all respects to the tongue 7 at the opposite end of the wall 4, is provided. From the corner 95 2 at which the tongue 10 is located, the wall 4 is curved inwardly against the inwardly curved edge of the section 3 to the opposite corner 2, there being tongues 11, the edges of two of which are close to the edges of the 100 adjacent tongues 7 and 10, respectively. Beyond the end tongue 11 the wall 4 of the box has an extension 12 bent at a sharp angle against and glued to the inner side of the adjacent end of the wall 4 (Fig. 3).

These tongues which overlap the edge of the section 3 are secured thereto by glue and the section 1 is placed against the outer side of the section 3 and secured to the tongues of the side wall by glue.

From a beginning adjacent to the extension 12 the side wall 4 has an integral in-

wardly bent portion 13 extending to the opposite end of the wall 4 and, at its said opposite end, overlapping the extension 12. This portion 13 of the side wall is defined by 5 a score line 14 extending throughout the length of the side wall and along which the portion 13 is bent inwardly, as described.

Thus it will be seen that I have provided a horse shoe box construction in which 10 neither the top nor the bottom is easily detachable from the corresponding side wall and which, in this respect, overcomes an existing objection. The box may be manufactured by box making machines quite 15 rapidly and economically.

I claim:—

1. A box comprising an inside bottom forming sheet having an inwardly curving recess in one edge, and its remaining edge 20 curving continuously from intersection with the ends of said recess and being of greater diameter in any direction than the width of said recess, and forming sharp corners at the intersection with said recess; and a side 25 for said box comprising an elongated strip having notches in one edge, and tongues extending from said notches, bent inwardly against the outer side of said bottom sheet, one end of said strip being at one of said corners and the body of said strip being bent 30 around the curved edge of said sheet and against the edge of said sheet in said recess, and having its other end overlapping the inner side of said first end and secured thereto 35 for a distance above the curved edge of said sheet, an infolded portion along the upper

edge and throughout the extent of said wall and overlapping the overlapping portion of said wall, and an outside bottom forming sheet of the same shape as the inside bottom forming sheet secured to said tongues and having its edges extending beyond said wall. 40

2. A box comprising an inside bottom forming sheet having its edge divided into two reversely curved portions with the 45 tongues of said curved portions forming sharp angles or corners, a side for said box comprising an elongated strip having at one longitudinal edge, right angularly bent tongues formed by notching the said edge 50 of the strip, said side being arranged with the body of the strip engaging and following the contour of the reversely curved edge portions of the bottom sheet and with the tongues flatly secured to the under face of 55 said sheet, the ends of the strip being arranged to meet at one of the two sharp angles or corners of the bottom sheet and the opposing edges of the tongues arranged on opposite sides of the said sharp angles 60 or corners being cut on coinciding angles so as to mate and bisect the said sharp angles or corners, one of the ends of said strip having an extension positioned to be secured to the inner face of the other end so as to 65 connect said ends the full height of the side, an infolded portion at the upper edge of the said other end overlapping and secured to the inner face of said extension, and an outside bottom forming sheet secured 70 to the exposed faces of said tongues.

FRANK J. SCHLEICHER.
